UNITED STATES PATENT OFFICE.

ELIHANAN L. MOODIE, OF NEW YORK, N. Y., ASSIGNOR TO CHARLES H. GIL-
LESPIE, OF SAME PLACE.

DESIGN FOR AN ADVERTISING-BLANK.

SPECIFICATION forming part of Design No. 13,369, dated October 24, 1882.

Application filed May 1, 1882. Term of patent 3½ years.

To all whom it may concern:

Be it known that I, ELIHANAN L. MOODIE, a citizen of the United States, residing in the city and county of New York, in the State of New York, have invented and produced a new and original Design for Advertising or Art Blanks, of which the following is a specification, reference being had to the accompanying drawing or photographic representation, forming a part thereof, the said drawing or photographic representation being a face or side view illustrating my said design.

My said design relates to a novel configuration of that class of articles of manufacture known as "advertising" or "ornamental" blanks, sometimes termed "art-blanks;" and it consists in a novel configuration of the face or side of said blank for receiving or being impressed or marked with pictorial matter, as hereinafter set forth.

My said design comprises the representation of a hatchet having pictorial matter and including the circumferential shape or configuration of a hatchet, substantially as represented in the accompanying drawing or photographic representation, A being the head of the hatchet,

having the circumferential configuration usual to the head of the implement commonly termed a "hatchet." B is the representation of the handle of the hatchet, and having in like manner the usual circumferential configuration or contour of a hatchet-handle, and having thereon the letters and word "G. Washington;" but the representation of the handle and the letters and word "G. Washington" may be omitted when desired.

The representation of the head of a hatchet may be colored or tinted in any desired or appropriate manner, and is to be provided on one or both sides with pictorial matter, substantially as shown in the photographic representation. When desired, any suitable advertising-matter may be printed or impressed upon the surface or surfaces of the design.

What I claim as my invention is—

The design for an art-blank, substantially as herein shown and described.

ELIHANAN L. MOODIE.
